UNITED STATES PATENT OFFICE.

FRIEDRICH OBERHÄNSLI, OF BREGENZ, AUSTRIA-HUNGARY.

INTERNAL-COMBUSTION ENGINE.

1,005,457.

Specification of Letters Patent. Patented Oct. 10, 1911.

Application filed November 28, 1910. Serial No. 594,558.

To all whom it may concern:

Be it known that I, FRIEDRICH OBERHÄNSLI, a citizen of Switzerland, residing at Bregenz, in the Empire of Austria-Hungary, have invented certain new and useful Improvements in and Relating to Improvements in Internal-Combustion Engines, of which the following is a specification.

This invention has reference to internal combustion engines of that type provided with compressed air ignition and in which the ignition period is determined by the moment at which the oil is injected. This is effected shortly before the engine piston reaches its dead center by the piston of a fuel pump which is operated from the engine. The injection at the end of the compression permits of a high compression of the mixture without producing premature ignition.

In order to effect a thorough mixing of the fuel with the air for combustion, the combustion chamber in accordance with the present invention is constructed in such a manner that the fuel issuing from the atomizer nozzle completely fills this chamber. The injection of the oil begins at the same moment of time while the actual period of spraying is shortened in proportion as the load on the engine decreases. The flow of fuel is not interrupted by the back stroke of the pump piston but by the opening of an overflow valve so that the injection of the fuel is caused to cease immediately and with a certainty. The atomizer nozzle which is arranged between the admission and exhaust valves in the cylinder head and beneath the pump piston is constructed in such a manner that the issuing fuel forms a wide cone of atomized oil which completely fills the hemispherical combustion chamber. As the fuel from the atomizer nozzle rains down, so to speak on to the air a thorough mixing takes place, so that with the high compression very complete combustion is obtained.

An embodiment of the invention is illustrated by way of example in the accompanying drawing in which:

Figure 1 is a vertical section of the cylinder head, the valves and the atomizer nozzle, and Fig. 2 is a similar view at right angles to Fig. 1, but with pump chamber and fuel nozzle shown in elevation.

The vertical engine, which, generally speaking, is of ordinary construction, is provided with an admission valve *a* and an exhaust valve *b* in the cylinder head. The atomizer nozzle *c* is arranged centrally between these two valves and loosely mounted therein is an atomizer valve *d* having its stem 55 projecting into a fuel pump cylinder *e'*, which is provided with a piston *e* normally held in its upper position by means of a coil spring *e*². On the upper end of the atomizer valve stem is a collar *d'* and interposed between same and the bottom of the pump cylinder is a coil spring *d*² for normally holding the valve *d* against its seat *d*³. A piece *c'* above the aperture of the nozzle *c* forms an abutment for the valve *d* 60 when in its lowest position. Arranged laterally of the pump is a suction valve *f*, and in the cylinder head is an overflow valve *g*. Oil is admitted through the pipe *h'* which is connected with passage *h* leading to the suction valve *f* from which extends an opening *h'* communicating with the top of the pump cylinder. The overflow valve *g* is normally held against its seat *g*' by means of a coil spring *g*² and connected with the top of the 65 pump cylinder *e'* by a channel *i* which extends to the opening *h'*. Leading from the overflow valve *g* to the oil reservoir is a pipe *k*. The suction valve *f* prevents the oil from being forced backward through the 70 passage *h* during the downward stroke of the piston *e* and the escape of the oil in excess from the pump cylinder is made through the channel *i* and overflow valve *g* to relieve the pressure on the valve *d* to 75 80 allow same to close quickly.

The pump is operated from the engine shaft by the operating lever *l* which is pivoted at *l'* to a support *l*² projecting from the cylinder head and rocked by means of 85 the rod *m*. The operating lever *l* is connected by a link *n* with the regulating lever *o* which actuates the overflow valve *g*. The regulating lever *o* is rotatably mounted on an adjustable eccentric *p*' provided with a 90 95 100

handle p^2 and mounted on a stud p fixed to the support l^2 . The supply of oil to the engine, the exact movement of the injection and the duration is regulated, according to 5 the nature of the oil employed, by the movement of the pump piston e and the operating of the overflow valve g , which are controlled by the adjustment of a set screw carried by the operating lever l and adapted to engage the pump piston e , and the adjustment of a set screw r of the regulating lever o , which screw is adapted to engage the stem of the overflow valve g . By rotating 10 the eccentric p' clockwise on the stud p its center rises and hence the pivotal point of the regulating lever o is raised and the screw r rises and it takes a longer movement of the lever o before the screw r engages the valve stem of the overflow valve g and therefore the time of the opening of the overflow valve is delayed relatively to the stroke of 15 the pump piston, as both the levers l and o are operated by the rod m ; and the opposite takes place as the eccentric is rotated counter-clockwise thereby lowering its center and the center of the fulcrum of the lever o .

The operation of the machine is as follows: During the first stroke only pure air 30 is drawn through the inlet valve a and this is compressed during the second stroke. At the end of the compression the pump piston e is forced downward, thereby exerting pressure on the oil in the pump cylinder e' 35 and forcing the valve d from its seat d^2 against the piece c' which prevents the aperture of the atomizer nozzle c being closed, whereby a fine oil mist cone issues from the atomizer nozzle c , permeates the hot combustion air, is partially vaporized and intimately mixed with the air. The cylinder head is considerably hotter than the cylinder itself and acts somewhat as a vaporizer. 40 The hemispherical combustion chamber which is adapted to the conical form of the fuel issuing from the atomizer nozzle and located immediately above the engine piston from which projects a cone s' , assists the intense combustion and can readily be freed 45 from exhaust gases. When the pump piston has forced the fuel in the form of a fine mist cone through the atomizer nozzle into the combustion chamber, the injection ceases immediately so that the explosion will take 50 place with certainty and exactly at the dead center. In order to attain this result the injection of fuel must cease suddenly and at a given moment, and for this reason the pressure is dissipated above the atomizer 55 valve by the opening of the overflow valve g . As soon as the pressure exerts itself toward the overflow, the relatively strong spring of the atomizer valve will close the latter and thus prevent the discharge of further fuel

from the atomizer nozzle. When the ignition has taken place, the expansion takes place during the third stroke and the exhaust during the fourth stroke. 65

Having fully described my invention what I claim is:—

1. In an internal combustion engine of the compressed air ignition type, the combination with the power cylinder of a combustion chamber at the end thereof, an atomizer nozzle arranged to open into the combustion chamber, a cut-off valve in the atomizer nozzle, a spring for normally holding the cut-off valve in closed position, a pump for forcing the liquid fuel through the atomizer nozzle past the cut-off valve, an overflow valve, an operating lever for the pump actuated from the engine shaft, a stud, an eccentric adjustably mounted on the stud, a regulating lever mounted on the eccentric and adapted to control the overflow valve, 70 and a link connecting the regulating lever with the operating lever whereby the pump and the overflow valve are operated according to the speed of the engine, substantially as described. 75

2. In an internal combustion engine of the compressed air ignition type, the combination with the power cylinder of a hemispherical combustion chamber at the end thereof, a piston in the cylinder and carrying a cone adapted to project into the combustion chamber, an atomizer nozzle arranged in alinement with said cone, a cut-off valve in the atomizer nozzle, a spring for normally holding the cut-off valve in closed position, a pump for forcing liquid fuel through the atomizer nozzle past the cut-off valve, a spring for normally holding the pump piston in its upper position, an overflow valve, an operating lever, a set screw 100 on the operating lever and engaging the piston of the pump, an adjustable eccentric, a regulating lever mounted on the eccentric and carrying a set screw for engaging the stem of the overflow valve, a link connecting 105 the regulating lever to the operating lever at the same side of their pivotal points, and means for actuating the operating lever from the engine shaft whereby the pump and the overflow valve are operated according to the 110 speed of the engine, substantially as described. 115

3. In an internal combustion engine of the compressed air ignition type, the combination with the power cylinder of a combustion chamber at the end thereof, an atomizer nozzle arranged to open into the combustion chamber, a cut-off valve in the atomizer nozzle, a spring for normally holding the cut-off valve in closed position, a pump cylinder connected with the atomizer nozzle, a piston in the pump cylinder, a spring for holding the pump piston in its retracted po 120 125

sition, an overflow valve, a spring for normally holding the overflow valve in closed position, an operating lever actuated from the engine shaft, adjustable means carried 5 by the operating lever for engaging the pump piston, an adjustable eccentric, a regulating lever mounted on the eccentric, a link connecting the regulating lever with the operating lever, and adjustable means carried

by the regulating lever for opening the over- 10 flow valve, substantially as described.

In testimony whereof I have affixed my signature in presence of two witnesses.
